Des. 204,985
Patented June 7, 1966

204,985

COAXIAL CROSS-POINT RELAY

Coenraad Van Loo, San Jose, Calif., assignor to Jennings
Radio Manufacturing Corporation, San Jose, Calif., a
corporation of Delaware

Filed Feb. 1, 1965, Ser. No. 83,635

Term of patent 14 years

(Cl. D26—13)

Fig - 2

Fig - 3

FIG - 4

FIG - 6

FIG - 5

FIG. 1 is a perspective view of the coaxial cross-point relay.

FIG. 2 is an elevational view of one side of the relay.

FIG. 3 is an elevational view of the back side of the relay as viewed in FIG. 2.

FIG. 4 is an elevational view of the relay as viewed from the bottom of FIG. 2 but with the relay shown turned end-for-end.

FIG. 5 is a plan view as seen from above in FIG. 1.

FIG. 6 is a plan view as viewed from the bottom of FIG. 1.

I claim:

The ornamental design for a coaxial cross-point relay, as shown.
